UNITED STATES PATENT OFFICE.

GEORGE ASHWORTH AND ELIJAH ASHWORTH, OF MANCHESTER, COUNTY OF LANCASTER, ENGLAND.

DOFFER-COMB HEAD FOR CARDING-ENGINES.

SPECIFICATION forming part of Letters Patent No. 397,266, dated February 5, 1889.

Application filed February 27, 1888. Serial No. 265,461. (No model.) Patented in England January 5, 1887, No. 144.

To all whom it may concern:

Be it known that we, GEORGE ASHWORTH and ELIJAH ASHWORTH, engineers, subjects of the Queen of Great Britain and Ireland, and residing at Manchester, county of Lancaster, England, have invented certain Improvements in Doffer-Comb Heads for Carding-Engines, (for which we have obtained a patent in Great Britain, No. 144, dated January 5, 1887,) 10 of which the following is a specification.

Our invention relates to the mechanism whereby rapid vibratory movement is imparted to the doffing-combs of carding-engines. The parts whereby the said movement 15 is directly obtained are ordinarily inclosed in a metal box. Owing to the high speed of movement of the parts which are in frictional contact, it is of great importance that the bearings and rubbing surfaces shall be well 20 lubricated, and that the lubricant should be prevented from escaping from the box and bearings. In the present practice oil-holes are provided whereby oil is introduced to the bearings; but we have found that these holes 25 also give access for the entrance of grit and dirt into the bearings and into the oil in the box or inclosed space, the oil being thereby rendered less efficient as a lubricant and the wear of the parts being increased. An additional 30 disadvantage of the present arrangement is that the oil is apt to escape past the bearings and find its way to the comb-shaft and comb. To remedy these defects we close the box, so that it shall be as air-tight as is 35 practically possible, the ordinary oil-holes in the shell of the box not being provided, and we provide means whereby a supply of oil or other suitable lubricant can be introduced into the box, and we so construct the box as 40 that all intercepted exuding oil shall be carried outside of the box into a dripper.

Our invention will be best described with reference to the accompanying drawings.

Figure 1 is a vertical section of the comb-motion mechanism, taken at the line of section coinciding with the axial line of the comb-shaft, parts being in elevation. Fig. 2 is a similar view at right angles to Fig. 1. Fig. 3 is a plan view of the box with the cover removed 50 and the revolving drip-catcher represented in

horizontal section. Fig. 4 is a vertical cross-section of the drip-catcher. Fig. 5 is a detached view of the fastening for the band-pulley, which is formed in one piece with the drip-catcher.

55

In Figs. 1, 2, and 3, *a* is the comb-motion box, which is formed as a hollow pedestal provided with a cover, *b*, which is secured to the box by means of four screws, *c c c c*. The box *a* contains a certain amount of oil, which is indicated by the shade-lines, the said oil being introduced into the box through a hole in the cover *b*. To close this hole, and also to provide means for gaging the amount of oil in the box, we introduce a plug, *d*, having a reduced extension, *d'*, which dips into the oil in the box and affords a ready means of ascertaining the depth. Instead of the gage-plug, we may use a gage hole or cock in the side of the box. The oil is maintained in the box at a suitable level, so that the vibrating arm *e* within the box shall dip into the oil and effect the lubrication of all of the bearings by the splashing of the oil. The gage *d* is provided as a guide to maintain the oil at the proper level, as it is important that there should not be an excess of oil in the box lest such excess should interfere with the rapid vibratory motion of the arm *e*. The arm *e* is actuated in the ordinary manner from a short spindle, *f*, driven by a pulley, *g*, on the end of the spindle. The neck *f'* of the spindle *f* is made conical, and the sliding block *h* in the arm *e* is also formed with inclined bearing-surfaces, so that by adjusting the bush *i*, which is screwed into the side of the box and jammed by the nut *i'*, the wear of these parts can be taken up. By the splashing of the arm *e* the oil is thrown up to lubricate the bearings of the comb-shaft *e'*. Owing to the rapid churning action of the crank and arm, it would be next to impossible to prevent oil from exuding through the bearings of the comb-shaft and also through the joint which the cover *b* makes with the box. We therefore form an intercepting-channel, *j*, in the box and covers. This channel extends entirely around the cavity of the box, and opens into a chamber, *l*, which is an enlargement of the opening through which the comb-shaft passes to the outside of the box. 100

This chamber intercepts any of the oil which works through the bearing and prevents it from passing to the outside of the box. The oil intercepted by the channel *j* also flows into this chamber. A shield-plate, *w*, half of which is attached to the box *a* and the other half to the lid *b*, closely encircles the comb-shaft, (shown in dotted lines,) and still further checks the egress of oil from the box. If the oil were returned directly into the interior of the box, the oil would churn up the passage into the chamber *l* and the channel *j*, and would escape and be wasted, and also such escaping oil would pass onto the comb-shaft and damage the sliver. We drain the chamber *l*, by means of a passage, *m*, and a spout, *n*, into the drip-catcher *o*, which is formed in one piece with the band-pulley *g*, and is fixed upon the spindle *f* so as to revolve with it. If preferred, the drip-catcher and the pulley may be separate parts.

In the example the passage *m* is bored in the metal of the walls of the box, and it will be seen that it has no direct communication with the interior of the box but only through the bearings and the joint between the cover and the box. The revolution of the drip-catcher is utilized to return the oil to the box. The oil is returned by means of a pipe, *s*, which is formed or provided with a mouth-piece, *s'*, which catches the oil as it is carried around and diverts it into the pipe *s*, through which the oil flows into a passage, *s*², and passes into the box. If found requisite, a vent-hole may be bored in the lid *b* immediately opposite the arm *e*. The pipe *s* is made a nice fit in the bored passage *s*², and is adjusted by turning the pipe within the passage. When adjusted, the pipe is fixed by means of a screw, *t*. The drip-catcher is passed into position when

the mouth-piece *s'* is turned into the position indicated by the dotted lines in Fig. 4, the mouth-piece being afterward turned into working position.

In Figs. 1 and 3 flats appear upon the pipe *s* in order that it may be turned by means of a key. When the drip-catcher is in position, a thin shield, *u*, is passed into position, and is secured to the turned boss *q*. This shield just clears the revolving drip-catcher and checks the entry of dust and fluff into the drip-catcher and the bearing of the spindle *f*. The said shield also gives the apparatus a neater appearance and boxes the parts in, leaving only the pulley *g* exposed. The drip-catcher, with its pulley *g*, is secured to the spindle by means of a nut, *v*.

The boss of the pulley or drip-catcher is made slightly taper, and is formed with a screw-thread, and is also split, as shown at Fig. 5, so that when the nut is tightened the spindle is firmly gripped.

We claim as our invention—

The combination of the comb-shaft, its operating-spindle, and connecting devices with the comb-motion box, having a channel, *j*, in the box and its cover to intercept the exuding oil, a passage, *m*, and a spout, *n*, leading therefrom, and a drip-catcher carried by the operating-spindle and into which the spout emp- ties, all substantially as described.

In testimony whereof we have signed our names to this specification in the presence of two subscribing witnesses.

GEO. ASHWORTH.
